UNITED STATES PATENT OFFICE.

CHARLES M. HUNTINGTON, OF EAST RANDOLPH, NEW YORK.

WASHING MACHINE.

Application filed March 12, 1923. Serial No. 624,571.

To all whom it may concern:

Be it known that I, CHARLES M. HUNTINGTON, a citizen of the United States, residing at East Randolph, in the county of 5 Cattaraugus and State of New York, have invented a new and useful Washing Machine, of which the following is a specification.

This invention relates to washing machines, the primary object of the invention being to provide a washing machine designed to clean by suction, thereby eliminating wear on the articles under operation.

10 Another object of the invention is to provide means for adjusting the article engaging head of the washing machine thereby adapting the machine for use in cleaning a greater or less number of articles.

15 Another object of the invention is to provide a construction to permit of the ready removal of the article engaging head to facilitate the filling of the article supporting receptacle.

20 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the 25 invention.

Referring to the drawing:

Figure 1 is a side elevational view of a washing machine constructed in accordance with the invention, the article engaging head and supporting beam being shown in dotted lines as in an adjusted position.

Figure 2 is a sectional view taken on line 2—2 of Figure 1.

Figure 3 is a sectional view taken on line 45 3—3 of Figure 1.

Figure 4 is an elevational view of the washing machine parts thereof being shown in section.

Figure 5 is a sectional view taken on line 50 5—5 of Figure 4.

Figure 6 is a sectional view taken on line 6—6 of Figure 4.

Referring to the drawings in detail, the reference character 5 designates the supporting platform which is mounted on the supporting legs 6.

An arm 7 is secured to the under side of the platform 5 and depends therefrom, the lower extremity of the arm extending at right angles and formed with a bearing 8, 60 in which bearing operates the lower end of the shaft 9 that carries the pinion 10.

The upper end of shaft 9 supports the head 11 to which is secured the container 12 which is preferably circular in cross section 65 to conform to the curvature of the article engaging head 13 which is mounted therein.

A shaft 14 is supported under the platform 5 and carries a worm gear 15 at the inner end thereof, which worm gear meshes 70 with the pinion 10 to impart rotary motion thereto, the shaft 14 receiving its motion through the pulley 16, which in turn has connection with a suitable power device not shown, through the usual belt, not shown.

75 The reference character 17 designates an arm which is secured to the platform 5 adjacent to one end thereof by means of the bolts 18, the upper end of the arm 17 being constructed to provide ears 19 between 80 which the pivoted arm 20 is supported.

Formed at opposite ends of the arm 20 are upwardly extended arms 21 and 22 respectively, which arms provide supports for the rod 23, on which is mounted the weight 85 24, which is held against movement longitudinally of the rod by means of the set screw 25. Due to this construction, it will be obvious that the weight 24 may be adjusted longitudinally of the rod 23, and held in 90 such positions of adjustment by means of the set screw 25.

The forward end of the arm 20 is cut away to accommodate the ear 26 formed on the bracket 27, which ear is apertured to accommodate the shaft 28 that also extends through the arm 20 as clearly shown by Figure 4 of the drawings, so that the bracket 27 may pivot in a vertical plane with respect to the arm 20.

100 Formed at the outer ends of the bracket 27 are openings to accommodate the shaft 29, which shaft is designed to rotate within the openings, suitable means such as washers 30 being provided to restrict movement of the shaft 29 through the openings. At the lower end of the shaft 29 is mounted the head 13, the head being secured to the shaft to move therewith, and as shown, the construction of the arm 20 and bracket 27 is 105 such as to normally support the shaft 29 at an angle to the end that the article engag-

ing head 13 operates at an angle with respect to the bottom wall of the container 12 for purposes to be hereinafter more fully described.

- 5 The head 13 is preferably dish-shaped and formed of sheet metal, corrugations being formed therein to present a roughened surface to grip the articles under operation, and prevent movement of the head 13 with respect to the articles, when the machine is in operation.

10 A peripheral flange 31 is formed on the head 13 and extends upwardly from the head, so that a relatively wide surface will be presented at the periphery of the head to eliminate wear of the articles by contact with the edge of the head.

15 Reference character 32 designates the cover for the receptacle 12 which is formed with an elongated opening 33 to permit the shaft 29 to extend therethrough, a cover plate 34 being also provided to close the opening 33 but permit of movement of the shaft transversely of the cover 32 when the 20 shaft is being adjusted.

25 The operation of the device is as follows:

The head, together with the shaft 21 is removed from the container 12 and the articles to be cleaned, together with a suitable 30 cleaning fluid, are placed in the receptacle. The arm 20 is now moved to a position to cause the head 13 to engage the articles in the container, the weight being now adjusted to cause the head to exert a pressure on the 35 articles in the container.

The shaft 14 is now rotated, which in turn, imparts rotary movement to the shaft 9 and container 12. Since the articles in the container are held between the bottom of the 40 container and head 13, it is obvious that the head 13 will rotate with the container 12, to the end that the articles positioned under the head are placed under pressure at one side of the container when the container is 45 rotated, while the pressure is relieved at the opposite side thereof. Upon continued rotation of the container 12, it will be seen that a suction is created at the high side of

the head 13, to remove foreign matter from the articles being washed.

50 When the articles have been thoroughly cleaned it will be noted that the arm 20 may be tilted to remove the head from the container, whereupon the articles may be removed and articles to be cleaned, placed 55 therein.

What is claimed as new is:—

1. In a washing machine, a platform, a rotatable container on the platform, a pivoted supporting arm mounted above the platform, a pivoted bracket at one end of the supporting arm, means for adjusting the supporting arm, a shaft supported by the bracket, and a head on the lower end of the shaft and positioned in the container. 60

2. In a washing machine, a platform, a rotatable container positioned on the platform, a pivoted arm supported above the platform, a bracket pivotally supported at one end of the arm, said bracket having 70 bearings, an angularly disposed shaft mounted to rotate in the bearings, a circular head at the lower end of the shaft and operating in a plane at an oblique angle with respect to the bottom of the container, and means for holding the pivoted arm in various positions of adjustment. 75

3. In a washing machine, a platform, a container supported on the platform, an adjustable arm supported above the platform, 80 a rod supported by the arm and disposed in spaced relation therewith, a weight on the rod and adapted to be adjusted longitudinally thereof, a shaft pivotally supported at one end of the arm, and a head mounted on 85 one end of the shaft to operate in a plane at an oblique angle with respect to the bottom of the container.

In testimony that I claim the foregoing as my own, I have hereto affixed my signature in the presence of two witnesses.

CHARLES M. HUNTINGTON.

Witnesses:

FLORENCE HOVEY,
E. A. WHEELER.
